UNITED STATES PATENT OFFICE.

LEWIS S. WATRES, OF SCRANTON, PENNSYLVANIA, ASSIGNOR OF FIFTY-ONE ONE-HUNDREDTHS TO CLARENCE D. SIMPSON, OF SCRANTON, PENNSYLVANIA.

LUBRICATING APPARATUS.

1,017,935.

Specification of Letters Patent. Patented Feb. 20, 1912.

Application filed August 30, 1911. Serial No. 646,887.

To all whom it may concern:

Be it known that I, LEWIS S. WATRES, a citizen of the United States, residing at Scranton, county of Lackawanna, State of Pennsylvania, have invented certain new and useful Improvements in Lubricating Apparatus, of which the following is a specification.

The purpose of this invention is to automatically lubricate by finely divided graphite, moving parts, such for instance as the pistons of steam and other engines and of air and other pumps and compressors.

The graphite is in the form of a stick or coherent body and by means of apparatus operated by the engine or other apparatus it is subjected to a grinding, cutting or abrading operation, the resulting graphite powder being distributed to the contact surfaces of the moving parts.

An embodiment of the invention that is practical and efficient is that disclosed in the drawing forming part of this application, in which the invention is shown applied to a steam or other fluid pressure engine and the graphite in the form of a bar or stick is intermittently subjected to a grinding or abrading operation brought about by the operation of the engine, the resulting powder being taken up by the fluid medium operating the engine and by it distributed to the moving surfaces in contact.

In the illustrated embodiments of the invention the grinding operation is effected by variation of pressure of the engine operating fluid medium, and by the action of a moving part of the engine.

In the drawing: Figure 1 is a view partly in elevation and section: Fig. 2 is a detail sectional plan of the construction shown in Fig. 1: Fig. 3, a side elevation showing a reciprocating engine equipped with the invention: Fig. 4 is a detail sectional plan showing a modification: Fig. 5, a sectional elevation showing a further modification: Fig. 6 is a section on the line VI, VI of Fig. 5; and Fig. 7 is a detail section showing another modification.

An ordinary double acting steam engine cylinder 1 has associated with it a usual steam chest 2. In a tapped aperture in the top of the steam chest is screwed the tubular threaded reduced end 3 of a hollow body 4. Within this body is rotatably mounted a cutting or grinding wheel 5 upon the periphery of which bears a stick or bar of graphite 6 seated in a vertical tubular extension 7 of the body and urged, if desired, against the wheel by a spring 8. The wheel 5 may turn upon or with its shaft 9 and has operatively associated with it a feed ratchet wheel 10. At the end of a lateral tubular extension 11 of the hollow body is a motor diaphragm 12 confined at its periphery and having applied centrally to its outer face a coiled compression spring 13 whose reaction tends to force the diaphragm inward. Attached centrally to the inner face of the diaphragm is a plunger 14 guided in a bearing 15 and carrying at its inner end a drive pawl 16 that engages the ratchet wheel 10. The pawl has applied to it a spring 17 that maintains it in engagement with the ratchet wheel. The confined space at the outer surface of the diaphragm is connected by a pipe 18 with the steam space of the cylinder adjacent one end thereof. When this latter end of the cylinder receives steam, the pressure thereof supplementing the reaction of spring 13 causes the diaphragm to move inward and when that end of the cylinder is exhausting and the other end is receiving steam the diaphragm will be forced outward.

In this way, during the operation of the engine, there is imparted intermittent rotation to the grinding wheel. The resulting graphite powder is taken up by the steam and by it carried to the various interior surfaces of the engine such as those of the cylinder and piston, and the controlling valve 90 and its seat.

It is not intended to confine the invention to a rotary grinder, nor to actuation of the grinder by variation of pressure in the interior spaces of the engine.

In Figs. 3 and 4 the construction and op-

eration of the grinding devices may be substantially the same as already described. The actuation of the grinding device is, however, effected from a moving part of the 5 engine. The shaft of the grinder passes outside of the hollow body 4 and has applied to its outer portion the ratchet wheel 10 that is intermittently actuated by the drive pawl 16 operated as shown by a moving 10 part 20 of the engine. That is to say, the reciprocating part 20 carries a projection 23 that intermittently strikes the end of an endwise moving rod 24 surrounded by a spring 25 that normally retracts it. 15 The other end of the rod is operatively connected with one end of a rocking lever 26 whose other end has pivoted in it the drive pawl 16 that engages the ratchet wheel 10, the latter in this construction being located, 20 Fig. 4, outside the shell.

In Fig. 7 a reciprocating grinder is shown. It may be in the form of a segment 21 intermittently actuated as shown in Fig. 1 through the medium of rod 14 and a link 22. 25 In Figs. 5 and 6 the shaft 9 passes out of shell 4 and carries (as in Fig. 4) the driving ratchet wheel 10. Within the shell is a frame 27 that reciprocates at right angles to shaft 9 and is formed with a slot through 30 which the shaft passes. The frame slides back and forth on a dovetail way 28 on the side wall of the shell and carries at each end a rod 29 that slides in tubular extensions from the shell. The cutting, grinding or 35 abrading surface 30 is in the form of an inverted V at the top of the frame. The frame is reciprocated by a cam 31 on shaft 9 working between rollers 32 on stud projections on the frame.

40 In the various forms in which the invention may be embodied the grinding chamber may be connected with one end, or both ends, of the cylinder.

In this invention the graphite supplied to 45 the reservoir or holder to be acted upon by the cutting, abrading or grinding means is in the form of a solid—that is a mass or body that retains its form under all conditions of use when unconfined and has such 50 physical characteristics as that the cutting, abrading or grinding devices act to remove finely divided lubricating particles therefrom.

I claim:

55 1. Lubricating apparatus, comprising the combination of a receptacle adapted to hold a mass of lubricant in the form of a solid, automatically operated means for removing from said solid finely divided lubricating 60 particles, and means whereby the lubricating particles may be transferred to the surfaces to be lubricated.

2. Lubricating apparatus, comprising the combination of a receptacle adapted to hold

a mass of lubricant in the form of a solid, 65 automatic intermittently operated means for removing from said solid finely divided lubricating particles, and means whereby the lubricating particles may be transferred to the surfaces to be lubricated. 70

3. The combination with an engine, of lubricating devices comprising a hollow body and within said body means for holding a mass of lubricant in the form of a solid, and means for cutting from said mass 75 lubricating particles, means whereby said lubricating particles are conveyed to the interior surfaces to be lubricated, and means for operating said cutting means during the operation of the engine. 80

4. Lubricating apparatus for an engine driven by a fluid medium under pressure, comprising a hollow body adapted for communication with the surfaces to be lubricated and within said body means for holding a 85 mass of graphite in the form of a solid and means for removing from said mass finely divided lubricating particles, and means adapted to be automatically operated for actuating said means for removing particles 90 from said mass.

5. Lubricating apparatus for an engine driven by a fluid medium under pressure, comprising a hollow body adapted for communication with the surfaces to be lubricated 95 and within said body means for holding a mass of graphite in the form of a solid and means for removing from said mass finely divided lubricating particles, and means adapted to be automatically operated for 100 variation of pressure in the cylinder for actuating said means for removing particles from said mass.

6. The combination with the steam chest of an engine of a hollow body communicating with the interior of the chest, means within said body for holding a solid mass of graphite in the form of a solid, means also within said body for removing from the mass of graphite finely divided lubricating 110 particles and means automatically operated to actuate said means for removing particles from said mass. 105

7. The combination with the steam chest of an engine of a hollow body communicating with the interior of the chest, means within said body for holding a mass of graphite in the form of a solid, means also within said body for removing from the mass of graphite finely divided lubricating particles and means automatically operated by 115 variation of pressure in the cylinder to actuate said means for removing particles from said mass. 120

8. The combination with the steam chest 125 of an engine of a hollow body communicating with the interior of the chest, means within said body for holding a mass of

graphite in the form of a solid, means also within said body for removing from the mass of graphite finely divided lubricating particles and means comprising a motor dia-
5 phragm automatically operated by variation of pressure in the cylinder to actuate said means for removing particles from said mass.

In testimony whereof, I have hereunto subscribed my name.

LEWIS S. WATRES.
